FUEL SUPPLY MECHANISM FOR GASOLINE STOVES

George E. Pickup, Newark, Ohio, assignor to
Newark Stove Company, a corporation of
Ohio

Application November 27, 1936, Serial No. 113,028

2 Claims. (Cl. 158—81)

This invention relates to valve controlled means for supplying fuel from the usual pressure supply tank to the burner mechanism of a gasoline stove, and more particularly concerns the simplification of the operations necessary to be performed by the user, as well as the promotion of a higher degree of safety in operation.

Gasoline stoves of the type now in use are provided with means for initially supplying to the generator burner a quantity of vaporized fuel taken from the supply tank and, after the generator has become heated, to supply liquid fuel thereto for vaporization in the continued operation of the stove. This involves several distinct valve operations by the user at spaced intervals of time and therefore requires close attention, together with a proper understanding of the order and time of operation of the individual valves.

With the foregoing in view, one object of the invention is to provide for the supply of fuel to the burner mechanism by means requiring only an initial valve setting operation by the user.

Another object is to provide a fuel supply mechanism automatically operable after a predetermined time interval to change the initial vaporized fuel supply taken from the supply tank for starting purposes, to liquid form for the continued or "running" operation.

A further object is to provide an improved fuel supply mechanism of this character, in which the starting fuel supply is controlled by pressure responsive valve means.

Another object is to provide a fuel supply mechanism of novel and advantageous character utilizing a combination of automatic pressure operated and thermostatic valves to control the starting and running conditions of the burner mechanism.

A general object is to provide a fuel supply mechanism capable of performing the aforesaid functions effectually, and which is simple in construction and reliable in operation.

The objects of the invention thus generally stated, together with other and ancillary objects and advantages are attained by the construction and arrangement shown by way of illustration in the accompanying drawings in which:

Figure 1 is a more or less diagrammatic plan view, partially in section, of a burner mechanism and associated fuel supply means embodying the invention.

Fig. 2 is a fragmentary sectional elevation taken approximately in the plane of line 2—2 of Fig. 1.

Fig. 3 is a fragmental sectional view taken approximately in the plane of line 3—3 of Fig. 2.

Fig. 4 is a fragmentary sectional view taken approximately in the plane of line 4—4 of Fig. 2.

Fig. 5 is a fragmental elevational view, partially in section of the starting tube assembly.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

My invention is particularly adapted for use in a gasoline cooking stove or range having burner mechanism of any suitable character. As shown herein, such mechanism may include a plurality of cooking burners, two being shown and designated, respectively, 10 and 11. These burners communicate with the manifold 12, and are under the control of suitable valve devices

13 and 14, respectively, arranged for convenient manual operation in the usual way. In normal operation vaporized fuel is supplied to the manifold by a generator 15 which is in the form of an elongated tube arranged to be heated in part by the burner 10. For this purpose the latter burner is herein formed in two sections disposed on opposite sides of the generator. Underlying the generator is an elongated auxiliary burner 16 that is in constant communication with the manifold 12. The discharge of vaporized fuel from the generator is under the control of the usual needle valve 17 having a stem 18 extending axially of the tube and projecting from the forward or inlet end thereof for operation by means of a suitable handle 19. The fuel issuing from the generator passes into a tubular goose-neck mixing chamber 20 which communicates with the manifold 12. In one side of this member is a suitable air inlet opening controlled by an adjustable plate 21.

A tank 23, herein of horizontally elongated form, is adapted to contain a supply of liquid fuel under air pressure. The front wall of the tank is formed as a head 24 having a fuel inlet 25, a pressure gauge 27 and a threadedly secured fitting 28. Within the fitting is an angular duct 29 one end of which communicates with the interior of the tank while the other end opens through an inlet nipple 30 to which is connected one end of an air conduit 32 (Figs. 1, 2 and 3). 55

The other end of this conduit is connected to a suitable hand pump 33 by which the necessary air pressure may be developed within the fuel tank.

5 Under the force of the air pressure, fuel is supplied from the tank 24 both for "starting" and for "running" purposes. To this end the fitting 28 is equipped with tubular means depending therefrom into the tank for communication with 10 the top and bottom portions thereof, and valve means operative to effect the supply, first of a rich mixture of air and fuel vapor and thereafter liquid fuel.

As shown in Figs. 2 and 5 the tubular means 15 referred to comprises in part two parallel starting fuel tubes 34 and 35 arranged to extend inwardly and downwardly within the tank for withdrawing therefrom the rich mixture of air and vapor for starting purposes. The tube 34 20 is connected at its upper end with the inner or lower end of the fitting 28 and constitutes a main supply tube. The tube 35 is in the nature of an auxiliary or vapor tube having its upper end near the top of the tank above the maximum 25 fuel level therein which is indicated at 37. At their lower ends the tubes are connected through the medium of a chambered cylindrical member or head 33 which serves as a combined metered intake and atomizing chamber. Air pressure 30 within the tank forces the carbureted fuel air mixture upwardly from the main tube 34 into a passage 39 formed in the fitting 28. For a more detailed description of a pre-generating or carbureting mechanism of this character attention 35 is invited to my copending application Serial No. 614,901 filed June 2, 1932, now Patent No. 2,067,412, issued January 12, 1937.

According to the present invention, the initial 40 supply of air and vapor from the upper portion of the supply tank, enriched by atomization of liquid fuel in the carbureting head 33, is controlled for delivery automatically for a predetermined interval of operation designed to prepare the burner mechanism to receive and utilize 45 efficiently liquid fuel. This enables an arrangement of the fuel supply mechanism such that only an initial valve adjustment by the user is required when lighting a stove which will thereafter automatically attain full operating 50 efficiency.

With the foregoing in view, the fuel supply mechanism herein is provided with valve means 55 which is sensitive to pressure variations within the supply tank 23 for controlling the flow of starting fuel to the burner mechanism. Such valve means, indicated generally by the numeral 40 (Fig. 2), may conveniently be mounted on the fitting 28 which may have for this purpose a rigid support or base flange 41 (Fig. 3). One side of this flange has a flattened hollow 60 face 42 through which opens a branch passage 43 that communicates with the fuel passage 39. Marginally encircling the hollow face 42 is an axially projecting rim or shoulder 44 which is 65 opposed by an internal, axially facing shoulder 45 of a hollow cap 47. The latter is threaded onto the base flange and forms therewith a chamber 48. Held tightly between the shoulders 44 and 45 and transversely separating the chamber 70 48 is a diaphragm 49. This diaphragm is preferably a thin, slightly dished metallic disk which is biased for axial movement normally away from the face 42 of the base flange into a position as shown in broken line in Fig. 3.

75 Suitably secured axially to the diaphragm 49

is a generally round hollow stem 50 which projects into a passageway 51 that communicates with the pressure chamber axially through the face 42 of the base flange 41, and is connected at its outer end with the burner mechanism of 5 the stove. The passageway 51 may be formed in a tubular bushing 52 suitably threaded into the base flange and has a portion 51a of restricted diameter to provide a shoulder 53 serving as a seat for a resilient composition valve element 54 10 carried at the end of the stem 50. This valve element is mounted upon an axially movable plunger 54a which protrudes from the stem 50 and is maintained in extended position by a coiled compression spring 55. The spring serves 15 to relieve the valve element 54 from excessive pressure and thus avoids sticking against the valve seat 53.

As shown, the form and length of the valve stem 50 are such that when the diaphragm 49 is 20 in its biased position, the valve element 54 is unseated, thereby permitting fuel vapor to escape from the pressure chamber 48 past the valve stem and out through the restricted portion of the passageway 51. To close the valve, force is 25 applied axially along the stem 50 in opposition to the bias of the diaphragm, herein through the medium of resilient means such as a coiled compression spring 56 which is located in an axial bore 57 provided for this purpose in the cap 30 41. One end of the spring bears against a cup-shaped plunger 58 which abuts the diaphragm, and the other end is seated within the hollow face of a tension screw 59 which is threaded into the bore 57. A lock nut 60 holds the tension 35 screw in any adjusted position.

The tension of the spring 56 is adjusted to act against the diaphragm with a force that is substantially balanced by the normal bias of the diaphragm 49 supplemented by the working pressure within the fuel tank 23 which is transmitted to the valve side of the diaphragm by the passages 39, 43 in the fitting. As a result, any increase in fuel pressure will act to overbalance the spring, and the diaphragm will snap into the open valve position to permit delivery of a starting fuel supply. In practice, a pressure differential of about 3 to 5 pounds in the tank above the usual working pressure of approximately 30 pounds has been found ample to cause the valve to remain open throughout the starting operation. The time interval of such operation will, of course, be predetermined by the rate at which withdrawal of starting fuel exhausts the surplus pressure.

Liquid fuel for running purposes is withdrawn from the lower portion of the fuel tank 23 through a tube 61 (Fig. 4) which extends from the fitting 28 and has a strainer head 62 located near the atomizing head 33. At its upper end the tube 62 registers with one leg of an angular liquid fuel passage 63 within the fitting. A manually operable flow controlling valve 64 seated within the duct 63 has a threaded stem 65 which carries a handle 67 at its outer end. In the form shown, a half turn of the valve stem 65 is adapted to carry the valve from the closed or "off" position to the open or "on" position, and the handle may be provided with suitable markings to advise the user of such positions.

Starting fuel and liquid fuel are conducted from the fitting 28 through conduits 68 and 69, respectively, (Fig. 1) which lead to the generator 15. Delivery of the liquid fuel, however, is controlled to follow the starting operation after a 75

predetermined interval during which the generator is heated sufficiently to vaporize the liquid fuel. This interval is preferably coordinated substantially with the interval during which 5 there is a starting pressure differential in the fuel tank. To this end, the conduits may be connected with a thermostatic valve device 70. Such device may comprise a casing 71 fixedly mounted laterally spaced from the generator 10 tube upon one end of a transversely extending bracket 72. Interiorly, the casing is formed with a pair of intersecting flow passages 73 and 74 which connect with the conduits 68 and 69, respectively. 15 The passage 73 provides uninterrupted communication between the starting fuel delivery conduit 68 and a common delivery pipe 75 which is connected to the inlet end of the generator tube. Communication between the liquid fuel 20 passage 74 and the delivery pipe 75 is interrupted, however, by a valve 77 which is carried upon one end of a thermo-responsive rod 78 arranged to be heated in the operation of the burner mechanism. Preferably, the rod extends from 25 the valve casing between the generator tube 15 and the generator burner 17 and is fixedly connected at its outer end to the opposite end of the bracket 72. Thus, only starting fuel will be delivered to the generator until the thermostatic 30 rod has been heated sufficiently to open the valve 77. Thereafter, if starting fuel continues to be delivered it supplements the liquid fuel during the initial part of the running operation and then will cease when the pressure in the fuel tank 35 drops to close the starting valve 54. Upon the discontinuance of the application of heat to the generator tube 15, the supply of fuel will quickly be interrupted by contraction of the rod 78 which will cause the valve 77 to close. 40 It will be apparent that, by the construction and arrangement set forth the operation of gasoline stoves may be greatly simplified. To start the burner mechanism the user need only pump the tank pressure slightly above that necessary 45 for running purposes, turn the liquid fuel valve handle 67 to the "on" position, open the generator needle valve 17, and light the generator burner 15. Thereafter the stove will automatically arrive at the running condition. Thus the 50 user is relieved of the necessity of attending the stove to effect a change in the fuel supply means from the starting to the running conditions thereof. As a result, the general utility of stoves of this character is substantially increased.

I claim as my invention:

1. In combination in a fuel delivery system for a stove including a generator and a burner, a fuel tank, starting and running fuel conduits leading from said tank to said generator, valve means mounted on said tank for controlling fuel flow through said conduits, a valve casing supported at a substantial distance laterally from said burner and generator so as to remain unheated and having a liquid fuel passage therein 10 communicating with the running fuel conduit, a valve member within said casing for controlling said passage, a delivery duct communicating at its inlet end with said passage and at its outlet end with said generator, a rod of thermo-responsive material lying between said generator and burner fixed at one end and carrying the valve member at the other end to move the same axially to open or close said liquid fuel passage upon expansion or contraction respectively of the 15 rod, and a starting fuel passage within said casing by-passing said valve and communicating at one end with said starting fuel conduit and at the other end with the inlet end of said delivery duct. 20

2. Fuel supply mechanism for gasoline stoves comprising, in combination, a fitting to be mounted upon the fuel tank of the stove and having separate tubes extending fixedly therefrom adapted for withdrawing liquid fuel and 25 vaporous fuel respectively from the tank, said fitting having a body including a passage leading from the liquid fuel tube to convey the liquid fuel to a fuel conduit, a manually operable valve mounted in said body to control said liquid-fuel 30 passage, a surface on said body having one passage opening therethrough in communication with the vaporous-fuel tube and a second passage opening therethrough adapted to communicate at its opposite end with a vaporous-fuel 35 delivery conduit, an enclosure for said surface providing a chamber affording communication between said one passage and said second passage, and a valve for controlling the second passage including means within said chamber normally 40 operative to hold said valve in passage-sealing position but being responsive to predetermined vaporous-fuel pressure in said chamber to open said valve so that vaporous fuel entering said chamber from said one passage may escape 45 therefrom through said second passage. 50

GEORGE E. PICKUP.
